UNITED STATES PATENT OFFICE.

ALBERT R. BRADEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

METHOD OF MAKING PATTERNS FOR CASTINGS.

Application filed November 22, 1920. Serial No. 425,855.

To all whom it may concern:

Be it known that I, ALBERT R. BRADEN, a citizen of the United States, residing at Beverly, in the county of Essex and State 5 of Massachusetts, have invented certain Improvements in Methods of Making Patterns for Castings, of which the following description, in connection with the accompanying drawings, is a specification, like reference 10 characters on the drawings indicating like parts in the several figures.

This invention relates to methods of making patterns for castings, being especially applicable to the manufacture of such articles as clicking dies, which are in the form 15 of closed figures of irregular contours. The production of these dies from strip steel in the manner usually followed, involving the heating of the stock and its gradual formation about a templet, is an operation requiring much skill, and is relatively slow and expensive. While it is feasible to cast the dies in sand molds at a small cost, as far 20 as the casting operation itself is concerned, the production of the patterns for making the molds has been so troublesome as to 25 bar their use in the casting of dies, of which, like clicking dies, but few are cast from each pattern.

30 An object of the present invention is to provide a simple procedure by which patterns may be made with a proper degree of accuracy at slight expense. This object I attain by first forming a strip of flexible 35 material having the cross-section of the object to be cast, and then bending the strip to the contour of said object. After thus producing the pattern proper, it is preferably mounted upon a carrier, to which it 40 may be secured by an adhesive. In the herein particularly described method of pattern making, the pattern strip consists of plastic material, preferably given the desired cross-sectional form, as of the clicking die stock, 45 by forcing it through an opening similarly formed. The cost of such a strip is trifling, and its after treatment easy.

A further object of the invention is to furnish a pattern in which the shrinkage of 50 the casting is provided for. This is accomplished by holding the templet and pattern strip in a predetermined relation during the formation of the latter to the templet, to cause the pattern to be of such size that

the shrinkage will be allowed for. When the 55 pattern strip has an inclined wall, as when it corresponds to clicking die stock, co-operation between the templet and strip at varying portions of the inclination will correspondingly alter the size of the pattern, 60 permitting it to be made to the desired degree larger than the finished casting. The correct relation between the strip and templet may be attained by mounting the templet parallel to a supporting surface, placing 65 the base of the strip upon the surface, and bending the strip to the templet.

Convenient means for performing the 70 steps of my improved method and a pattern for a die made in accordance therewith are illustrated in the accompanying drawing, in which

Fig. 1 shows an apparatus for producing the strip of pattern material;

Fig. 2 illustrates in perspective the arrangement of the templet with relation to the support and the co-operating strip during the step of bending;

Fig. 3 is transverse section therethrough; 80 and

Fig. 4, a perspective view of the completed pattern.

In making a pattern for use in casting clicking dies, there is first formed a pattern strip S , which is of generally triangular 85 form, having a base s and opposite converging walls inclined from the base, the inner of these walls, when the strip assumes the contour of the die, being designated by the letter i . For this purpose I prefer to employ a 90 plastic material, as beeswax, a mass M of which may be placed in a cylinder 10 of some such strip-producing apparatus as is illustrated in Fig. 1 of the drawing. This cylinder is shown as carried upon a suitable base 95 in a horizontal position, and has an upwardly extending tube 12 , through which the plastic may be introduced. The tube is closed by a head 14 , and to enable pressure to be exerted upon the introduced mass to sufficiently fill the cylinder, the head is carried 100 by a screw 16 threaded through a yoke 18 , which may be separably fixed across the top of the tube. With the yoke and head removed, the plastic is placed, if necessary in successive charges, through the tube, and forced into the cylinder, upon the return of the head and yoke, by screwing down the

former. At one extremity of the cylinder is a cap 20, from which is a reduced extension 22, shown as rectangular in cross-section, the lower wall of this extension being horizontal. In one of the side walls, and also along the bottom of the extension, is an opening 24, which, in the side wall, has a form corresponding to the section of a strip of clicking die stock, or to that of the die itself before it is sharpened. Bearing against the bottom wall of the extension and closing the opening therein is a table 26, mounted for movement in a horizontal direction upon pairs of rollers 28, 28, the journals 30 of which are arranged to travel along depressions in spaced supporting bars 32, 32 extending transversely of the base of the apparatus. Operating in the opposite end of the cylinder is a plunger 34, carried upon a threaded rod 36 arranged to turn in a bearing 38. Surrounding the rod, adjacent to the bearing, and having threaded engagement with the former, is a worm-wheel 40. With this worm-wheel meshes a worm 42 fixed upon a shaft 44 journaled upon the base. The shaft carries a pulley 46 belted to a suitable source of power, which may be caused to communicate its rotation to the worm by means of a friction clutch 48. The rotation of the worm will be transmitted to the worm-wheel, which will cause the longitudinal travel of the rod 36 and therefore the advance or retreat of the plunger 34 through the cylinder, the advancing movement pressing the plastic through the opening 24. It there emerges upon the table 26 in the form of the pattern strip, carrying the table with it upon its rollers, this continuing until a strip of the desired length has been formed. If necessary, the mass within the cylinder may be warmed by a fluid-conveying pipe 50 coiled about the cylinder, the flow through this being controlled by a valve 52.

The formed strip is then to be bent to the outline of the die to be cast, this being best accomplished by the use of a templet, as is indicated at T in Figs. 2 and 3, the external contour of which templet is that of the cutting edge of the die. The templet is mounted upon and parallel to a base or support 54, having suitably spaced openings 56, 56 to receive posts 58 extending vertically through the support. Upon the posts are enlargements 60, on which the templet may rest, it being locked on each post by a wedge-shaped key 62 having a key-hole slot 64, the circular portion of which receives the full diameter of the upper extremity of the post, while the narrowed extension admits a reduced portion 66.

With the keys removed, templet openings are carried over the posts, the keys returned, and the templet locked by forcing the wedges to one side, so that their slots travel along the reduced portion 66 of the post. To per-

mit the distance between the support and the templet to be varied, the posts are movable through the support openings, being urged outwardly from the base by helical springs 68 situated between the base and the post enlargements. The outward movement of the templet is adjustably limited by means of nuts 70 engaging the threaded ends of the posts.

There having been determined the amount which the cast metal will shrink to reduce the transverse dimensions of the die from that of the mold space in which it is cast, the templet is adjusted by turning the nuts 70 until its distance from the support 54 is less than that between the base of the pattern strip and its apex. Consequently, when the inclined wall of the strip engages the templet, the transverse dimensions of the pattern which is produced in accordance with the templet contour will be increased over that of the casting by an amount depending upon the distance between the support and templet and upon the angle of the side wall i. This adjustment of the templet may be caused to exactly compensate for the shrinkage.

This predetermined arrangement having been made, the base s of the flexible pattern strip is placed upon the support with its wall i toward the templet, and is bent in accordance with the contour of said templet, as is particularly illustrated in Fig. 2. When the strip has been thus formed about the entire periphery of the templet, its ends are joined, as by heating and pressing together, and its base is placed upon a mounting board or carrier B, both the board and strip being coated with an adhesive fluid, as shellac, which acts to secure the elements to each other and also to protect them—the board against the absorption of moisture and the strip against abrasion. This completes the pattern, which may be utilized in the customary way for producing a sand mold, in which a die may be cast. It will be seen that every step of the method may be performed quickly and accurately by means of simple instrumentalities, without any particular skill being required on the part of the workman, and that the materials employed are relatively cheap, and may be used repeatedly for the production of different patterns.

Having described my invention, what I claim as new and desire to secure by Letters Patent of the United States is:

1. The method of making patterns for castings, which consists in forming a strip of flexible material having the cross-section of the object to be cast, and bending the strip to the contour of said object.

2. The method of making patterns for castings, which consists in forming a strip of flexible material having the cross-section

of the object to be cast, bending the strip to the contour of said object, and fixing the formed strip upon a carrier.

3. The method of making patterns for 5 castings, which consists in forming a strip of flexible material having the cross-section of the object to be cast, bending the strip to the contour of said object, placing the formed strip upon a carrier, and applying 10 an adhesive to the strip and carrier.

4. The method of making patterns for 15 castings, which consists in forming a strip of plastic material having a cross-section corresponding to the object to be cast, and bending the strip to the contour of said object.

5. The method of making patterns for 20 castings, which consists in forcing a strip of plastic material through an opening having the form of a cross-section of the object to be cast, and bending the strip to the contour of said object.

6. The method of making patterns for 25 castings, which consists in forming a strip of wax under the influence of heat and pressure, bending the strip to the contour of the object to be cast, placing the formed strip upon a carrier, and applying shellac to the strip and carrier.

30 7. The method of making clicking die patterns, which consists in forming an opening corresponding to the cross-section of die stock, forcing plastic material through the opening to produce a pattern strip, bending the strip about a die templet, and mounting the strip upon a carrier.

35 8. The method of making patterns for 40 castings, which consists in forming a strip in accordance with a templet, the strip and templet during this formation being maintained in a predetermined relation to introduce into the pattern an allowance for shrinkage in the casting.

9. The method of making patterns for 45 castings, which consists in forming a strip of flexible material having an inclined wall, and bending the strip to bring the inclined wall into agreement with the templet at predetermined portions of its inclination.

10. The method of making patterns for 50 castings, which consists in forming a strip of flexible material having a base and an inclined side wall, mounting a templet parallel to a supporting surface, placing the base of the strip upon the surface, and bending the strip to bring the inclined wall into agreement with the templet.

11. The method of making patterns for 55 castings, which consists in forming a strip of flexible material having a base and an inclined side wall, mounting a templet at a predetermined distance from a supporting surface, placing the base of the strip upon the surface, and bending the strip to bring the inclined wall into agreement with the 60 templet.

12. The method of making patterns for 65 castings, which consists in mounting a templet in proximity to a support, fixing the templet in a position determined by the 70 casting to be produced, and forming a pattern strip about the templet upon the support.

13. The method of making clicking die 75 patterns, which consists in forming a pattern strip corresponding in cross-section to clicking die stock, mounting a die templet at a distance from a support determined by the casting to be produced, placing the base of the pattern strip upon the support, and bending an inclined wall of the strip into 80 agreement with the templet.

In testimony whereof I have signed my name to this specification.

ALBERT R. BRADEN.
